MAXWELL M. UPSON, OF ENGLEWOOD, NEW JERSEY, AND HERMAN R. SMITH, OF NEW YORK, N. Y.

FORMING AND DRIVING COMPOSITE PILES.

1,245,289.

Specification of Letters Patent.

Patented Nov. 6, 1917.

Application filed June 3, 1916. Serial No. 101,456.

To all whom it may concern:

Be it known that we, MAXWELL M. UPSON and HERMAN R. SMITH, citizens of the United States, residing at, respectively, 5 Englewood, county of Bergen, and State of New Jersey, and New York, county and State of New York, have invented certain new and useful Improvements in Forming and Driving Composite Piles, of which the 10 following is a full, clear, and exact description.

Certain conditions have developed in the use of composite piles, *i. e.* those composed in part of wood and in part of reinforced concrete, which have militated against their adoption by engineers. One of these is a practical method of holding the wood pile in its connection with the driving pipe or mandrel so that a vertical position of the 20 ultimate structure is assured. Another is the difficulty of making a safe joint between the concrete and the wood sections. A satisfactory pile must have a practically uniform cross sectional strength in order to 25 withstand any uneven lateral action. This is accomplished in elements of this character by reinforcing rods, which are secured to the wood either by screw construction or other suitable method and embedded in the super- 30 imposed concrete, the concrete having a known and definite frictional value in its contact with the steel. Furthermore, owing to the method of construction heretofore used, the concrete portion has had practi- 35 cally the same frictional carrying capacity as the wood portion for the reason that the concrete portion of the pile has been of a uniform cross sectional area, which provides only vertical frictional area. In the con- 40 struction shown in the present method, the concrete portion of the pile has a uniform taper and consequently provides greater friction and materially increases the carrying capacity of the pile.

45 This invention deals with the three difficulties thus stated, and which have not heretofore been met in an entirely satisfactory manner.

While efforts have been made to get a 50 satisfactory composite pile wherein the concrete is pre-cast and attached to the wooden member and then the entire structure driven, such efforts have been open to the objection that the operation of driving tends

to shatter the concrete, particularly at and 55 about the zone of union with the wood as well as about the head of the pile, thereby impairing the structure. In driving the pile, we use a collapsible mandrel fitted snugly with an outer sheeting of suitable 60 material, preferably sheet metal, which at its lower end is secured by a boot to the top of a wooden pile or sectional piling, which makes a substantial water tight joint be- 65 tween the said casing or sheathing and the pile. The bottom of the lower end of the mandrel contains a circular opening into which is fitted the top of the wooden pile. This provides a rigid connection between 70 the mandrel and the wooden pile and assures a vertical alinement of the wooden pile during its emplacement. The mandrel ex- tends to the bottom of the sheeting and con- 75 tains a driving core with a head which, when all the parts are assembled, rests on the top of the wooden pile and drives the latter, to- 80 gether with the sheathing, to any depth that may be required below the water or the sur- face of the ground.

The parts are so constructed and arranged 80 that when the wood pile has been driven to the required depth, the mandrel is collapsed and withdrawn from the sheathing, leaving the latter as an extension of the pile and adapted to be filled with concrete up to the 85 desired level. It will be observed that all the advantage of carrying power due to the compression of the adjacent earth when driving a tapered pile and in maintaining 90 this compression during the period while 95 the form is being filled, is provided in the upper or concrete portion of the composite structure.

In order to convey a clear idea of the plan which we follow in uniting the concrete and wooden portions of the pile and driving the same to place, we preface the specific de- 95 scription hereinafter given with the follow- ing somewhat general statement:

The wooden end and provision for the 100 concrete portion of the completed pile com- 105 prising the corrugated metal casing or sheathing are primarily united by a water tight joint, so that after the wooden pile is driven, the concrete may be packed into the superposed shell and united directly to the wood, while water and silt are excluded by the watertight joint referred to. Moreover,

the concrete portion, as well as the wood, may be made tapering, so that the upper surface area as well as the lower compresses the surrounding earth and makes a stronger support for any load which the pile may be called upon to support than if the pile were made with straight sides, as has been heretofore required.

Another feature of improvement resides in the use, in connection with the driving core of the mandrel, of a movable perforated head through which rods screwed into the end of the wooden pile extend when the parts are assembled for operation. This head drops down to the end of the truncated end of the tubular core of the mandrel before the latter is passed on the top of the wooden pile, so that the reinforcing rods which complete the union of the concrete and wood may be readily and easily passed up through the holes therein.

These and other details of our invention will be described more fully by reference to the accompanying drawings, in which,

Figure 1 is part of a central vertical section of the means for forcing and driving the composite pile, and

Fig. 2 is a similar view of the complete pile, after the driving mandrel has been withdrawn and the corrugated casing filled with cement or concrete.

The means for driving the pile comprise an exterior expandible or collapsible tubular mandrel A and an inside driving core B. Over the former, which is tapered, fits a casing or shell C of corrugated sheet metal wrapped or wound with a wire D and carrying at its lower end a boot E, which is composed of a ring F and a cup-like extension which surrounds the end of the sheathing. The lower end of the mandrel tube extends to the bottom of this annular cup, as clearly shown in Fig. 1.

The lower end of the driving core B is secured to a head H, from which depends a tube K and an extension L of the driving core, the extreme end of which fits into a socket in a driving head M.

This driving head is supported by rods N connected to slides O, which are adapted to travel in vertical slots P in the tube K, and when the wooden pile R is not in place the head M falls away from the extension L to the end of the outer tube A.

It is not necessary, for purposes of this case, to describe in any detail the construction or operation of the expandible mandrel, as this is a well known part of the prior art. Suffice it, therefore, to say that, when a pile is to be formed and driven the boot E, secured to the end of the corrugated casing or sheathing C, is passed down over the round and somewhat smaller end of the wooden pile R and made tight.

In the end of the wooden pile are screwed

rods G which extend upwardly for a sufficient distance therefrom to become firmly embedded in the concrete when that is packed into the casing C to securely unite and solidify in an integral structure the wood and the concrete. 70

When, therefore, the wooden pile and the casing C have been united, the mandrel is introduced into the casing and the rods G are caused to pass up through perforations 75 in the head M. As the latter drops to the end of the tubes A and K the registry of the rods G in these holes is very greatly facilitated.

After the wooden pile R, with the attached casing C, has been driven to the required depth, the mandrel is collapsed and withdrawn and the casing C packed with concrete, thus forming a reinforced concrete pile so securely anchored to the wooden portion R as to form an integral composite pile of any desired length and size. 80 85

In many respects the specific construction of the parts illustrated may be modified without departure from the invention, as 90 will be readily perceived by those skilled in this art.

When we specify a "water tight joint", it is intended to designate such a joint as will prevent the entrance to a substantially 95 injurious extent of water, silt or other foreign matter.

Our claims in this application are confined to the forming and driving of the pile herein set forth, other features being reserved for divisional applications. 100

What we claim as our invention is:

1. The method of forming and driving composite piles of wood and concrete, which consists in uniting by a water-tight joint to a wood pile at a point below its upper end, a tapering shell or casing of sheet metal of the dimensions of the upper portion of the completed pile, introducing into such casing a tight fitting expanding mandrel provided at its lower end with a hollow rigid portion that fits down over the upper end of the wooden pile until the mandrel rests on the top of the wooden pile, driving thereby the casing and the wooden pile, then collapsing and withdrawing the mandrel and filling the empty casing with concrete. 110 115

2. The method of forming and driving composite piles of wood and concrete, which 120 consists in uniting by a water-tight joint to a wooden pile at a point below its upper end, a tapering thin sheet metal casing which is ultimately to constitute a form for the concrete portion of said pile, introducing into said casing a correspondingly shaped and tight fitting expanding mandrel over the upper end of the wooden pile, so as to maintain the latter in vertical position, driving thereby the casing and the 125 130

wooden pile, then collapsing and withdrawing the mandrel and filling the empty casing above the wooden pile with concrete.

3. The method of constructing and driving a composite pile of wood and concrete, which consists in forming a tapered structure, the lower end formed of a wooden pile which is extended in the form and dimensions of a finished pile by a casing of thin sheet metal united to the wooden pile by a water joint at a point below the upper end of the same, inserting into the casing and down over the end of the wooden pile there-

in a tight fitting expanding mandrel, driving thereby the said wooden pile and its attached casing, then collapsing and withdrawing the mandrel and packing the casing above the wooden pile with concrete. 15

In testimony whereof we affix our signatures in the presence of two subscribing 20 witnesses.
